(57) **CLAIM**

The ornamental design for a raincoat, as shown and described.

DESCRIPTION

FIG. 1 is a perspective view of a raincoat, shown in use with the raincoat worn on a human body;

FIG. 2 is a perspective view of the raincoat, shown separately for illustration;

FIG. 3 is a front elevational view thereof;

FIG. 4 is a rear elevational view thereof;

FIG. 5 is a right side elevational view of the rain coat, where the visor of the raincoat is in a configuration of use;

FIG. 6 is a left side elevational view thereof;

FIG. 7 is an enlarged view of portion 7 shown in FIG. 6;

FIG. 8 is an exploded perspective view of the raincoat; and, FIG. 9 is a front elevational view of the raincoat, shown in use with the raincoat partially opened with a collar folded down.

The broken lines in the drawings depict stitching of the raincoat that form no part of the claimed design. The broken lines forming the face, hands, legs and boots in FIG. 1 depict environment and form no part of the claimed design. The line-dot-dot broken lines in FIGS. 6 and 7 depict boundaries of the claim and form no part of the claimed design.

1 Claim, 9 Drawing Sheets
